UNITED STATES PATENT OFFICE.

HARRY R. SINCLAIR AND CARL EKMAN, OF WORCESTER, MASSACHUSETTS; SAID EKMAN ASSIGNOR TO SAID SINCLAIR.

PIPE-WRENCH.

1,023,533.

Specification of Letters Patent. Patented Apr. 16, 1912.

Application filed August 28, 1909. Serial No. 515,122.

To all whom it may concern:

Be it known that we, HARRY R. SINCLAIR and CARL EKMAN, citizens of the United States, residing at Worcester, county of 5 Worcester, and State of Massachusetts, have invented an Improvement in Pipe-Wrenches, of which the following description, in connection with the accompanying drawing, is a specification, like characters on the drawing representing like parts.

This invention relates to pipe wrenches of that type wherein the pipe is gripped by a strap or other flexible member and which are commonly known to the trade as "strap 15 wrenches".

The objects of the invention are to provide a novel pipe wrench of this class which necessitates the use of a minimum amount of strap material and which is simple and 20 very inexpensive to manufacture.

As is well known one end of the strap of a strap wrench is usually secured to the head of the handle, while the other end is free therefrom. The most common way of securing the strap to the head has been to 25 form the end of a strap into a loop and then secure the loop to a shackle, pin, wedge, or other securing or anchoring device. Where the strap is thus formed into a loop, a considerable length of strap is used which is of 30 no value so far as gripping or encircling the pipe is concerned, and as the strap is the part of the wrench which needs renewing more or less frequently, and as the cost of 35 the strap depends upon its length, the wrench which requires the shortest length of strap for a given size of pipe has an advantage over other wrenches which require a longer length of strap.

Our improved wrench not only uses a minimum length of strap for a given size of pipe, but it is also so constructed that the strap can be readily removed therefrom or secured thereto whenever a change of strap 40 is necessary, and the means for securing the strap to the wrench are such as to obviate the possibility of improperly attaching the strap.

We will first describe one embodiment of 50 our invention and then point out the novel features thereof in the appended claims.

Figure 1 shows in perspective view a wrench embodying the invention; Fig. 2 is a longitudinal section; Fig. 3 shows the 55 wrench used in a different way from what

is shown in Figs. 1 and 2; Fig. 4 is a view of the wedge for securing the end of the strap to the wrench.

The wrench comprises in its construction the handle 3 having formed at one end the head 4 which terminates in the nose 5 as usual in this class of devices. The head is provided with two transverse passages or throats 6 and 7. The throat 7 is wedge shape and is adapted to receive an anchoring wedge 8 which is the means for anchoring or securing one end of the strap 9 to the head.

In the preferred embodiment of our invention the back or rear wall 10 of the wedge-shaped throat 7 is substantially perpendicular to the axis of the wrench handle, while the front wall 12 thereof is inclined. The back wall 10 has formed therein a groove 13 which extends from one end to the other of said throat and is preferably situated centrally, and the wedge 8 is provided with the rib 14 adapted to fit the groove 13. The front face 15 of the wedge is roughened, preferably by making it with serrations which run longitudinally of the wedge or transversely to the length of the strap.

In securing the strap to the handle, one end thereof is placed through the throat 7 without doubling the strap on itself, and it is only necessary that the end of the strap should just project through the throat. The wedge 8 is then inserted, as shown in Figs. 2 and 3, with the serrated face 15 in engagement with the strap and with the rib 14 occupying the groove 13. The serrated face 15 affords a greater frictional engagement with the strap than exists between the rear face of the wedge and the rear face 10 of the throat, and as a result when strain is put on the strap, the wedge will be drawn down into the throat 7 thereby more tightly gripping the end of the strap.

The wrench may be used in the usual way by passing the strap around the pipe 16 to be turned and then passing the free end of the strap over the nose and through the throat 6, as seen in Figs. 1 and 2, or the said wrench may be used by passing the strap through the throat 6 first then around the nose and pipe and back through the throat 6, as seen in Fig. 3.

It will be noted that there is no extra length of strap used at the end of the strap

which is secured to the head and that the length which is made into a loop in those devices which necessitate a loop in the strap is thereby saved.

5 The rib 14 and groove 13 serve to accurately guide the wedge and prevent it from becoming twisted in the throat, and the wedge will, therefore, bear evenly on the surface of the strap and there will be no 10 danger that the wedge will become twisted so as to bear with greater pressure on one edge of the strap than on the other.

In order to simplify the manufacture of the wrench, we have made the handle with 15 the web 20 extending from one side edge to the other and have provided for the requisite stiffness by forming the flanges 21 around the edge of the web. With this construction it is possible to readily cast the 20 handle in one piece and at the same time to use a minimum amount of metal consistent with the proper stiffness and strength. The rear wall 10 of the throat is formed by the flanges 24 which extend from the end of the 25 web 20, while the front wall is formed by one side of a bar 25 which extends across from one side to the other of the head. The rib 14 not only serves to guide the wedge, but the end of the rib on the narrow edge of 30 the wedge furnishes a surface against which a nail set, punch or other suitable tool may be readily placed when it is desired to drive the wedge out of the slot. The form of wedge herein shown has still another advantage 35 in that it makes it impossible for anyone to place the end of the strap improperly in the throat 7. In order that the strap may be securely held by the wedge it is essential that said strap be situated between 40 the wedge and the face 12 of the throat 7, for if the strap were placed against the face 10 of the throat and the wedge were inserted between the strap and the face 12, the pull 45 on the strap across the end of the wedge would prevent it from being pulled down into the throat as firmly as is possible where the strap is situated between the wedge and the face 12. By making the wedge with the 50 rib 14, therefore, it is impossible to place the strap on the wrong side of the wedge

and this is important because it insures that the strap will always be properly attached to the handle even by a person who is unfamiliar with the device.

Having fully described our invention, 55 what we claim as new and desire to secure by Letters Patent is:—

1. A pipe wrench comprising a handle having a head terminating in a nose and provided with two passages or throats, one 60 of which is wedge shaped, a strap having one end extending once only through the wedge-shaped throat, and a wedge fitting said throat and having a serrated face to engage the strap, the other face of the wedge 65 engaging the wall of the throat and said face and wall having coöperating means to prevent the wedge from twisting.

2. A pipe wrench comprising a handle having a head terminating in a nose and 70 provided with two passages or throats, one of which is wedge-shaped and is provided with a groove extending from one end to the other thereof on the back side, a strap having one end extending once only through 75 said wedge-shaped throat, and a wedge fitting the throat and provided with a serrated face to engage the strap and having a rib on its back side fitting said groove.

3. A pipe wrench comprising a handle 80 having a head terminating in a nose and provided with two passages or throats, one of which is wedge-shaped, a strap having one end extending once only through the wedge-shaped throat and lying against the wall 85 thereof adjacent the nose, and a wedge fitting said throat and having a serrated face to engage the strap, the opposite face of the wedge engaging the wall of the throat and said latter face and wall having one a depression and the other a raised portion to fit said depression.

In testimony whereof, we have signed our names to this specification, in the presence of two subscribing witnesses.

HARRY R. SINCLAIR.
CARL EKMAN.
